UNITED STATES PATENT OFFICE.

FRANK M. ROGERS, OF BALTIMORE, MARYLAND.

TENSION DEVICE FOR LOOM-SHUTTLES.

1,272,112.

Specification of Letters Patent.

Patented July 9, 1918.

Application filed May 31, 1917. Serial No. 171,953.

To all whom it may concern:

Be it known that I, FRANK M. ROGERS, a citizen of the United States, residing at Baltimore city and State of Maryland, have 5 invented and discovered certain new and useful Improvements in Tension Devices for Loom-Shuttles, of which the following is a specification.

My said invention relates to tension devices for loom shuttles, and consists in the 10 combinations and arrangements of elements hereinafter described and particularly set forth in the accompanying claims.

The invention has for its purpose to provide a device for regulating the tension on 15 the yarn in such a manner that any desired degree of adjustment may be obtained and wherein the adjusting member will not become loose and project beyond the surface 20 of the shuttle and thereby cut the warp threads as the shuttle passes through the shed.

The invention has for its further purpose to provide a device of this character which 25 will prolong the life of the shuttle, and wherein the tension regulating member is constructed to securely hold in set position under the blows which the shuttle receives.

The invention is disclosed by way of illustration in the accompanying drawings, 30 wherein:

Figure 1 is a plan view of a shuttle with the tensioning device applied thereto.

Fig. 2 is a similar view taken at right 35 angles to Fig. 1 and showing the tensioning device in detail, and

Fig. 3 is a detail view, partly in section, of a modified form of tension regulator.

Referring to the construction in further 40 detail, and wherein like reference characters designate corresponding parts in the different views shown, 4 designates a shuttle of well known type provided with a tension device involving a lever 5 pivotally mounted on 45 the pin 6 secured to the shuttle, and having the parts 7 thereof pressing against the yarn. A coming from the bobbin (not shown), and guide members 8 and 9 direct the yarn through the opening B in the bobbin after 50 the usual manner. The above described features of the shuttle form no part of the present invention, but are illustrated only to show the application of the tension adjusting device.

55 The tension device adjusting means consists of a bushing 10 that is screw threaded

within an aperture C in the shuttle, and is formed with a head or flange 11 that fits within a countersink 12 of the opening C, as shown. The head 11 is formed with a 60 notch 12^a to receive a screw driver or other like implement for applying the bushing or socket piece 10 into place, and in thus applying the piece the same is inserted 65 through the opening D with which the shuttles are usually provided.

A screw 13 is threaded into the socket piece 10, and has a relatively large head or flange 14 whose upper surface bears against the spiral spring 15 that engages the lever 70 5 and tensions the latter to give the desired pressure of the lever arm 8 against the yarn A. Said lever 5 is provided with a stud 16, to which the end of the spring 15 is connected or fits, as shown. It will, therefore, be seen that any adjustment on the screw 13 will tension the lever 5 through 75 said spring 15.

The screw 13 is preferably a split-screw, or slotted, as at 17, longitudinally of its 80 axis and spread slightly whereby to obtain a strong frictional grip between the threads of the screw and the internal threads of the socket piece 10, as will be understood. The slot 17 also serves to receive a screw driver 85 or other device for turning the screw to regulate the tension on the spring 15. The head 14 of the screw is preferably formed with a notch for turning the screw from the inside, since said screw is adapted to 90 be applied to the bushing 10 through the opening D in the same manner as that stated for applying said bushing.

The screw 13 will readily hold in the socket piece 10, and should it become loosened from any cause the threaded end of the screw will not project beyond the surface of the shuttle with the disastrous results noted, since the head of screw will contact with the inner end of the bushing 10. 100 Any fine adjustment desired on the yarn engaging lever end 7 may be obtained by inserting a screw driver or other tool into the split end of the screw from the outside of the shuttle.

In the construction shown in Fig. 3 the screw 13 is provided with a central projecting portion 18 that serves to receive the coil of the spring 15 that engages with the head 14 of the screw, and thereby center the 110 spring and hold the same against lateral displacement. The projecting portion 18 is

formed with a notch 19 to receive an implement for applying or adjusting the screw from the inside.

It will be seen from the foregoing that with having the socket piece 10 and screw 13 provided with the head pieces 11 and 14, respectively, the same cannot back out, or project beyond the body of the shuttle in such a manner as to cut the ends of the warp under the blows which the shuttle receives in passing through the shed.

Although I have illustrated and described a preferred form of the invention, I am aware that many modifications can be made therein by any person skilled in the art without departing from the scope of the invention as expressed in the claims. Therefore, I do not wish to be limited to all the details of construction herein shown and described.

What I claim as my invention and desire to secure by Letters Patent is:

1. A tension device for loom shuttles, comprising a member adapted to engage the yarn, a tensioning spring engaging said member, an apertured socket piece fitted in the shuttle, and a screw adjustable in said socket piece and engaging said spring, said screw being provided with a projecting part to prevent its passage through the socket piece, substantially as set forth.

2. A tension device for loom shuttles, comprising a member adapted to engage the yarn, a tensioning spring engaging said member, an apertured socket piece fitted in the shuttle, and a screw adjustable in the socket piece and having a head engaging said spring, said head preventing the passage of the screw through the socket piece, substantially as set forth.

3. A tension device for loom shuttles, comprising a member adapted to engage the yarn, a tensioning spring engaging said member, an apertured socket piece fitted in the shuttle, and a screw adjustable in the socket piece and having a head engaging said spring and preventing the passage of the screw through the socket piece, said screw having a notched end for adjusting the screw through the socket piece, substantially as set forth.

4. A tension device for loom shuttles comprising a member adapted to engage the

yarn, a tensioning spring engaging said member, a socket piece having internal and external screw threads fitted in the shuttle, and a screw adjustable in the socket piece and having a head engaging said spring and preventing the passage of the screw through the socket piece, said screw having a notched end for adjusting the screw through the socket piece, substantially as set forth.

5. A tension device for loom shuttles, comprising a member adapted to engage the yarn, a tensioning spring engaging said member, a socket piece screw threaded in the shuttle and having a head located within the shuttle, and a screw adjustable in the socket piece and having a head engaging said spring and preventing the passage of the screw through the socket piece, said screw having a notched end for adjusting the screw through the socket piece, substantially as set forth.

6. A tension device for loom shuttles, comprising a member adapted to engage the yarn, a tensioning spring engaging said member, a socket piece fitted in the shuttle, and a screw adjustable in said socket piece for tensioning said spring, said screw having a notched head for engaging the spring and applying the same to the socket piece, and formed with a notched end for adjusting the screw through the socket piece to regulate the spring tension, substantially as set forth.

7. A tension device for loom shuttles comprising a member adapted to engage the yarn, means for adjusting the tension of said member, a socket in the shuttle and means for securing the adjustment of the tension consisting of a screw adjustably mounted in said socket and operably connected with said member and having a head located between said member and the socket to prevent its passage through said socket, substantially as set forth.

In witness whereof, I have hereunto set my hand and seal at Baltimore, Maryland, this 28th day of May, A. D. nineteen hundred and seventeen.

FRANK M. ROGERS. [L. s.]
